UNITED STATES PATENT OFFICE.

CHARLES C. LEIGH, OF PHILADELPHIA, PENNSYLVANIA.

AIR BRUSH OR SPRAYING DEVICE.

Application filed July 15, 1925. Serial No. 43,663.

My invention consists of a novel construction of spraying device for spraying paint, pigment, or other material in a finely atomized condition upon any surface desired to be painted or decorated, my invention, however being particularly adapted to the spraying of paint or pigment upon glass, pottery, or similar surfaces.

In carrying out my invention I provide a suitable receptacle with a threaded cap upon which is supported a commingling tube and its adjuncts whereby the compressed air and pigment can be quickly and effectively commingled, means being provided for regulating the quantity of compressed air admitted and for also regulating the amount of the commingled compressed air and pigment discharged through the outlet port of the spraying device.

It further consists of a novel manner of mounting the spraying and controlling device with respect to a suitable receptacle.

It further consists of novel means for assembling the controlling devices for the compressed air supply and the spraying device, whereby the various parts can be readily assembled or dismantled for the purpose of inspection or repairs without requiring the aid of skilled labor.

It further consists of a novel manner of positioning a handle with respect to the receptacle and the compressed air device and the spraying device, whereby the various parts will be nicely balanced and can be readily conveyed to any desired point.

It further consists of other novel features of advantage and construction, all as will be hereinafter fully pointed out in the specification and claims.

For the purpose of illustrating my invention I have shown in the accompanying drawings forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation of a novel spraying device, embodying my invention.

Figure 2 represents a vertical sectional

view of Figure 1, certain of the parts being shown in elevation.

Figure 3 represents a detail view showing the manner of connecting the valve stem and flexible member which control the outlet nozzle of the spraying device.

Figure 4 represents a plan view of the right hand portion of the valve stem seen in Figure 2, showing the slotted and flanged portion thereof.

Figure 5 represents a view in detail to be hereinafter referred to.

Similar numerals of reference indicate corresponding parts in the figures. Referring to the drawings:

1 designates a receptacle which may be of metal or other suitable material, but preferably of metal, and provided with a window 2, so that the depth of the paint, pigment or other material contained within said receptacle may be readily visually ascertained. The top of the receptacle 1 is screw threaded to receive a screw threaded cap 3 which carries a vertically disposed bracket 4 which supports a longitudinally extended outer commingling tube 5, which is secured with respect to the bracket 4 by means of a screw 6. The tube 5 is provided with a union 7, and the cap 3 is provided with a vertically disposed pendant tube 8 which projects within the paint or pigment 32 to within a short distance of the bottom of the receptacle 1. Connecting the tube 8 and union 7 is a short pipe section 9 which has screw threaded relation with the socket 10 of the cap 3 and which is connected with respect to the union 7 by a nut 11 or its equivalent. One end of the tube 5 is provided with a spraying device 12 which is preferably flexible and is adapted to be manipulated during the spraying operation. The spraying device 12 has a ball and socket connection as at 13, with the tube 5 and is provided with the nozzle 14 which is preferably detachably connected to the tubular member 12. The opposite end of the tube 5 is provided with a hollow handle 15 adapted for detachable connection with a source of compressed air, (not shown). The upper end of the handle 15 is provided with a short section of pipe 16 movable vertically through which is a needle valve 17, operable by a handle 18 which has pivotal connection as at 19 with an extension 20 detachably connected with and carried by the tube 5, the upper end of the pipe 16 forming

ing a valve seat for the valve 17. Extending longitudinally through the tube 5 is a stem 21 slotted as at 22 through which passes the needle valve 17. The opposite end of the 5 stem 21 is provided with a flexible connection 23 which carries at its outer end a needle valve 24, which flexible connection 23 and valve stem 21 is under tension by reason of the spring 25, bearing against the flange 31, 10 and may be adjusted with respect to the outlet port of the nozzle 14 by means of the thumb screw 26. The tube 5 is provided with a handle 27 whereby the entire device may be transported from place to place.

15 In operation the paint, pigment, or equivalent material 32 is caused to be withdrawn from the receptacle 1, through the pipe 8 to the pipe 5 and flows around the valve stem 21 and the flexible connection 23, through 20 the outlet opening 33 of the nozzle 14. Compressed air is admitted through connection 28, through hollow handle 15 and connection 16 to pipe 5 when the handle 18 is actuated to compress the spring 29 and lift the needle 25 valve 17 from its seat in the connection 16. The compressed air flowing through the pipe 8 and connection 9, sucks up sufficient paint, pigment or other material from the receptacle 1 to cause an admixture of compressed 30 air, and the paint or pigment in an atomized condition has its egress through the outlet port 33 of the nozzle 14 in the form of a spray. By adjusting the nut 26 upon the screw threaded end 30 of the valve stem 21, 35 the desired adjustment of the needle valve 24 with respect to the outlet 33 may be secured to provide a proper admixture of the pigment and compressed air which is readily directed upon the desired point by reason 40 of the universal joint connection 13.

The rod or valve stem 21 may be provided with a guide head 34 of less diameter than the bore of the tube 5. The nut 35 can be readily adjusted on the threaded end 36 of 45 the valve 17, so as to adjust the throw of said valve.

It will be apparent that by reason of the threaded connections seen in Figures 2, 3 and 5, that the valvular member 24, as well 50 as the parts 21 and 23 can be readily assembled or disconnected, and the tubular member 12 can be readily disconnected from the tubular member 5 by means of the coupling nut 37. The nut 11 permits the ready disconnection of the tube 5 from the parts 8, 9, and 10, and by loosening the fastening devices 6 and 19, the various parts can be readily dismantled according to requirements. The threaded head 38 into which the valvular member 24 is screwed has its bearing 55 within the nozzle 14 and is readily reciprocated and guided therein, as is evident, said

head being smaller than the bore of the nozzle, so as to permit the ready discharge of the commingled compressed air and pigment 65 through the outlet port 33 of the nozzle 14.

Having thus described my invention what I claim as new and desire to secure by Letters Patent, is:—

1. In a spraying device a receptacle, a 70 cover therefor, a substantially horizontally extending tube mounted on said cover, a pendant tube extending therefrom to the interior of said receptacle, a universal joint in said horizontal tube, an outlet connection carried by said universal joint, a spraying nozzle in said outlet connection, a valvular member for controlling the outlet in said spraying nozzle, a horizontally disposed valve stem positioned in said horizontal tube, 75 and having a flexible connection to said valvular member in said spraying nozzle, a compressed air inlet, a valvular member controlling the compressed air inlet and passing through a slot in said valve stem, 80 means for actuating and controlling the compressed air valve and means for adjusting the movement of said air valve.

2. In a spraying device, a receptacle, a cap 85 therefor, a substantially horizontally disposed tube mounted on said cap, a pipe depending therefrom into said receptacle, a spraying nozzle on an extension of said tube, a compressed air supply at the other end of 90 said tube, a handle member through which said air passes, means for controlling the flow of said compressed air, a universal joint intermediate said nozzle and tube, and means for regulating the outlet area of the spraying 95 nozzle, said regulating means for the spraying nozzle being located in proximity to the compressed air controlling device.

3. In a spraying device, a receptacle, a 100 cover therefor, a substantially horizontally extending tube mounted on said cover, a pendant tube extending therefrom to the interior of said receptacle, a universal joint in said horizontal tube, an outlet connection carried by said universal joint, a spraying nozzle for said outlet connection, a valvular member for controlling the outlet in said spraying nozzle, a horizontally disposed valve stem positioned in said horizontal tube, and having a flexible connection to said valvular member in said spraying nozzle, a 105 compressed air inlet, a handle through which the compressed air passes, a valvular member vertically disposed and controlling the compressed air inlet and passing through a slot in said valve stem, means for actuating and 110 controlling the compressed air valve and means for adjusting the movement of said air valve with respect to its seat.

CHARLES C. LEIGH.
